Attorney

UNITED STATES PATENT OFFICE.

LUCIOUS SANDERS BRYANT, OF WEST PALM BEACH, FLORIDA.

FLASH-LIGHT.

1,334,835.

Specification of Letters Patent. Patented Mar. 23, 1920.

Application filed June 11, 1918. Serial No. 239,457.

To all whom it may concern:

Be it known that I, LUCIOUS S. BRYANT, a citizen of the United States, residing at West Palm Beach, in the county of Palm Beach and State of Florida, have invented certain new and useful Improvements in Flash-Lights; and I do hereby declare the following to be a full, clear, and exact description of the invention, such as will enable others skilled in the art to which it appertains to make and use the same.

This invention relates to improvements in flash-lights, and has for one of its objects the provision of a device of this character having convenient means for opening and closing the electric circuit to the electric lamp when desired.

Another object of this invention is the provision of a novel means for establishing an electrical connection between the battery, electric lamp, and the circuit closing means, and which is entirely protected by the casing while in use.

A further object of this invention is the provision of a flash-light of the above stated character, which will be simple, durable and efficient, and which may be manufactured and sold at a comparatively low cost.

With these and other objects in view, as will become more apparent as the description proceeds, the invention consists in certain novel features of construction, combination and arrangement of parts as will be herein-after more fully described and claimed.

For a complete understanding of my invention, reference will be had to the following description and accompanying drawing, in which:

Figure 1 is a side elevation of a flash-light constructed in accordance with my invention,

Fig. 2 is a vertical sectional view of the same, and

Fig. 3 is an end view, illustrating the circuit closing means.

Referring in detail to the drawing, the numeral 1 indicates a cylindrical casing constructed from insulating material and has each end open. A bottom closure cap 2, constructed of insulating material is secured to one end of the casing 1 by means of set screw 3 and carries a contact 4, which has one end disposed exteriorly thereof for engagement with a switch 5, while the opposite end engages the lower end of a battery 6. The battery 6 is located within the casing 1, and is

supported in spaced relation to the cap 2 by means of an enlarged portion 6' constructed of insulating material carried by the cap and the contact 4. The enlarged portion 6' is of hollow formation and has one end of a contact 7 located therein, and which contact is carried by a closure cap 2 in spaced relation to the contact 4. An insulated wire 8 is connected to the inner end of the contact 7, and extends out of the enlarged portion 6' upwardly along the wall of the casing 1, and is connected to a contact 10, carried by the upper end of the casing 1. The last-named end of the casing 1 has mounted thereon an externally threaded metallic collar 11, which engages the outer end of the contact 10. A sleeve 12 has one end internally threaded for co-operation with the screw threads upon the collar 11, whereby the sleeve is detachably secured to the casing 1. The sleeve 12 has formed therein a retractor 13, provided with an internally screw threaded socket 14 for receiving an electric lamp 15. The electric lamp 15 extends through the socket 14 for engagement with the upper end of the battery, as illustrated at 16. A lens-supporting member 17, carrying a lens 18, is secured to the outer end of the sleeve 12 for supporting the lens directly in front of the electric lamp 15 and the reflector 13.

The switch 5 consists of a bar that is pivotally connected to the contact 7, and has connected to its free end a handle 19 for swinging the bar into engagement with the contact 4, whereby an electric circuit is completed to the electric lamp. A stop 20 is carried by the closure cap 2, and is adapted to limit the movement of the switch 5 in one direction or when disconnected from the contact 4, as clearly illustrated in Fig. 3.

When it is desired to remove or replace the battery 6 in the casing 1, the sleeve 12 is detached from the casing 1, whereby the battery can be readily withdrawn or replaced in the casing, as desired.

While I have shown and described the preferred embodiment of my invention, it will be understood that minor changes in construction, combination and arrangement of parts may be made without departing from the spirit and scope of the invention as claimed.

Having thus described my invention, what I claim is:

A flash light including an insulated casing having each end open, a metallic sleeve de-

tachably secured to one end of the casing, a battery in said casing, a reflector formed in said sleeve and supporting an electric lamp in engagement with the battery, a cap closing the other end of said casing, a contact secured to the cap and engaging the battery and projecting exteriorly of said cap, a hollow insulated offset portion formed on the cap and engaging the battery for aiding in supporting the battery, a second contact secured to the cap and prevented from engaging the battery by said offset portion and extending exteriorly of the cap, means con-

necting the second named contact with the sleeve, and a switch member pivoted to the outer end of the second named contact and adapted to be moved into and out of engagement with the outer end of the first named contact. 15

In testimony whereof I affix my signature 20 in presence of two witnesses.

LUCIOUS SANDERS BRYANT.

Witnesses:

C. J. PETERSEN,
B. L. STEEN.
